TAPPET FACE

Gerald R. Bouwkamp, Royal Oak, Mich., assignor to Standard Screw Company, Hartford, Conn., a corporation of New Jersey

Application September 9, 1957, Serial No. 682,722

8 Claims. (Cl. 74—569)

This invention relates to hydraulic or mechanical tappets or valve lifters and has for one purpose to provide a tappet having a curved cam-contacting surface with more than one radius of curvature.

Another purpose is to provide a cam face for a hydraulic or mechanical tappet effective to produce tappet rotation with reduced peak contact stresses.

Another purpose is to provide a hydraulic or mechanical tappet cam face effective to produce tappet rotation with reduced peak contact stresses and a minimum edge loading between said cam face and a cam with which it is operatively associated.

Another purpose is to provide for uniform wear of a tappet cam face while maintaining a minimum reduced peak contact stress and preventing excessive edge loading between said cam face and a cam with which it is operatively associated.

Other purposes will appear from time to time during the course of the specification and claims.

I illustrate my invention more or less diagrammatically in the accompanying drawings, wherein:

Figure 1 is a side view illustrating a conventional cam and a hydraulic valve lifter or tappet;

Figure 2 is an end view in cross section taken on line 2—2 of Figure 1;

Figure 3 is a schematic detail view of a conventional spherical tappet cam face and a schematic representation of a tapered cam;

Figure 4 is a diagrammatic illustration of conventional cam and tappet cam-face contact areas;

Figure 5 is a graphic representation of a conventional tappet cam face radius;

Figure 6 is a schematic representation of one form of tappet cam face of my invention and a schematic representation of tapered cam;

Figure 7 is a representation of tappet cam face and cam-contact areas of the device illustrated in Figure 6;

Figure 8 is a graphic representation of the tappet cam face radii illustrated in Figure 6;

Figure 9 is a schematic showing of a variant form of tappet cam face of my invention and a schematic representation of a tapered cam;

Figure 10 is a representation of the tappet cam face and cam-contact areas of the device illustrated in Figure 9;

Figure 11 is a graphic representation of the tappet cam face radii illustrated in Figure 9;

Figure 12 is a diagram illustrating the geometric construction of a modified form and described in the specification;

Figure 13 is a diagram illustrating the geometric construction of the form of Figures 6, 7 and 8; and

Figure 14 is a diagram illustrating the geometric construction of Figures 9, 10 and 11.

The graphic representations of Figures 5, 8 and 11 are drawn with the abscissa as the path of the initial contact point across the tappet cam face and the ordinate

2

as the radius of curvature in the direction of the path at the point of contact.

Like parts and symbols are indicated by like numerals and letters throughout the specification and drawings.

Referring now to the drawings, and particularly to Figures 1 and 2, the numeral 1 generally represents a conventional cam shaft. The numeral 2 similarly designates generally a conventional cam. A tappet or valve lifter is shown generally at 3. The valve lifter has a cam face 4 constituting its lower surface and positioned for operational contact with the cam 2.

Figure 3 illustrates a typical spherical tappet cam face of conventional design and arranged to operate against a slightly tapered cam. The contact area at maximum lift and the two contact areas at maximum tappet velocities are illustrated by the shaded areas shown in the center and each side, respectively, of the diagram constituting Figure 4.

Referring particularly to Figure 4, the outer circle 5 illustrates a tappet diameter. The dotted lines 6, 6 designate the width of the cam 2 and therefore the width of the path of the cam 2. The dot and dash line 7 indicates the path of the initial contact point as the contact area moves back and forth across the cam face of the tappet with rotation of the cam as may be seen best in Figure 4. The path 7, in the case of the conventional design illustrated schematically in Figures 3, 4 and 5, is a straight line at a constant distance from a plane to the center line of the tappet and perpendicular to be axis of the cam.

For a given set of conditions, an increase in the spherical radius of the tappet will result in an increase in the length or major axis of the contact area and a reduction or lessening of the width or minor axis thereof. While such increase in the spherical radius of the tappet cam face results in a reduction of stress at the initial contact point at the center of the contact area where the peak stress occurs, such increase is limited by the requirement for precluding the contact area from running off the edge of the cam and consequent high loads at the cam edge as well as higher peak stresses at the initial contact point. Similarly, the variation in amount of offset effects the amount of edge loading and the degree to which the angle of the tapered cam can be controlled with respect to the center line of the tappet will effect the size of the tappet spherical radius. With larger spherical radii there is a greater effect on the amount of offset for a given change of angularity of the tapered cam. As indicated in Figure 5, the conventional spherical radius is constant.

Figures 6, 7 and 8 illustrate one form of my invention in which the radius of curvature of the cam face is constant from the center of the tappet out to a given diameter and from that diameter to the tappet O.D. it is constant but smaller or shorter than the initial radius.

In Figure 8 it will be noted that the path of the initial point of contact is offset within the circle 8 at which the two cam face surfaces are tangent. It will be observed further that the contact areas, illustrated for example at 4a, since they do not at these positions cross the circle at which the two surfaces are tangent, are elliptical in shape and their size and peak stresses will depend on the radius of curvature of the surface on which they occur. When the contact area lies across the tangent circle, the curve of compression will no longer be symmetrical, as indicated at the contact area at maximum lift and designated 5a in Figure 7. The major axis of the portion of contact area 5a falling outside the tangent circle 8 will tend to be shortened or blunted and

for a given load this will slightly increase the length of the major axis falling inside the tangent circle.

By selecting the proper diameter for the tangent circle, the contact area movement can be made less sensitive to variations in the angle of the tapered cam with respect to the tappet center line. Since the peak contact stress generally occurs near the nose of the cam when the contact area is near the center of the tappet, a reduction can be obtained through the use of two radii of curvature for the tappet cam face. The large center radius of the curvature combined with the smaller outer radius of the curvature, with the resultant non-symmetrical contact area, will permit lower peak stresses in the tappet than is possible with the conventional spherical, constant radius cam face while maintaining the same degree of protection against edge loading. Alternatively, increased protection against edge loading with the same peak stress is possible with the tappet cam face having two radii of curvature. The smaller radius of curvature of the outer curve will increase the stress level on the contact area when it falls outside the tangent circle. However, since these stresses are much lower than those near the nose of the cam, the use of two radii of curvature will have the effect of more uniformly distributing the stress level and wear over the cam face of the tappet.

The offset of the contact area will also be reduced when it lies on the outer surface having the smaller radius of curvature. With reduced offset the contact area will not come as close to the tappet O.D. at a given peak tappet velocity. Moreover, more positive control of tappet rotation is provided through control of the offset of contact area with the tappet cam face having two spherical radii.

As illustrated graphically in Figure 9, the two spherical radii of the tappet cam face of my invention may be rather sharply defined.

In Figures 9, 10 and 11 I illustrate a tappet cam face having a radius of curvature varying according to a smooth curve, illustrated graphically, for example, in Figure 11, when proceeding from the center of the cam face to the outside edge. As best seen in Figure 10, the path of the initial point of contact, indicated at 7b, is represented by a smooth arched line. The contact area at maximum lift, indicated at 5b, has an even more blunted end portion.

In the geometric construction of Figure 12 R_1 is the radius of curvature of the camface within the diameter D_x . R_2 is the radius of curvature of the camface between the diameters D_x and D_y . R_3 is the radius of curvature of the camface outside the diameter D_y . D_x and D_y are the diameters at which the three surfaces are tangent.

In the geometric construction of Figure 13 R_1 is the radius of curvature of the camface within the diameter D_x . R_2 is the radius of curvature of the camface outside the diameter D_x . D_x is the diameter at which the two surfaces are tangent.

In the geometric construction of Figure 14 the curved line from C_1 to C_2 is the locus of the centers of the radii of curvature. R_x is the radius of curvature at a diameter D_x . D_x is the diameter at which the two surfaces are tangent.

Although an operative form of the device has been shown, the invention is not limited to the particular details shown. Many changes may be made in the form, shape and arrangement of parts without departing from the spirit of the invention. It will be understood, for example, that a tappet cam face made up of three or more curved surfaces, each with its own constant radius of curvature and tangent to the adjoining surfaces, may be employed where desirable without departing from the nature and scope of the invention.

I claim:

1. A tappet having a cam face, said cam face having a plurality of radii generating spherical surfaces.
2. A tappet having a cam face, said cam face having a plurality of radii generating spherical surfaces, each of said radii defining a circle concentric with a circle defined by an adjoining radius.
3. A tappet having a cam face, said cam face having a curved surface, said curved surface a plurality of portions, each of said portions having a different radius of curvature.
4. The structure of claim 3 wherein each said radius of curvature defines a circle tangent to a circle definable by an adjacent radius of curvature.
5. The structure of claim 3 wherein said portions are two in number, the radii of curvature of said portions being positioned to define a tangent circle.
6. A tappet having a cam face, said cam face having a curved surface, said surface having a portion defined by a first radius and a second portion defined by a second radius, the curved surfaces formed by the two radii being tangent at the circle concentric with the center line of the tappet.
7. A tappet having a camface, said camface having a plurality of radii generating spherical surfaces, each of said radii defining a circle concentric with the center line of the tappet.
8. A tappet having a camface, said camface having a curved surface, said surface having two or more portions each defined by a radius of curvature, the portions formed by the radii being tangent at circles concentric with the center line of the tappet.
